United States Patent

Des. 241,566
Patented Sept. 21, 1976

241,566

TOY TRUCK

George T. Roberts, Mason, and Scott C. Dennison, Cincinnati, Ohio, assignors to General Mills Fun Group, Inc., Minneapolis, Minn.

Filed Apr. 14, 1975, Ser. No. 567,911

Term of patent 14 years

Int. Cl. D21—01

U.S. Cl. D34—15 AJ

FIG. 4

FIG. 5

FIG. 6

FIG. 1 is a side view of a toy truck illustrating our new design;

FIG. 2 is a view of the opposite side of the toy truck of FIG. 1;

FIG. 3 is a top plan thereof;

FIG. 4 is a bottom plan view thereof;

FIG. 5 is a front elevational view thereof; and

FIG. 6 is a rear elevational view of the toy truck.

We claim:

The ornamental design for a toy truck, substantially as shown.
